UNITED STATES PATENT OFFICE.

CLARENCE D. PLATT, OF BRIDGEPORT, CONNECTICUT.

ELECTRIC-SWITCH LOCK.

1,344,958.

Specification of Letters Patent. Patented June 29, 1920.

Application filed October 1, 1919. Serial No. 327,616.

To all whom it may concern:

Be it known that I, CLARENCE D. PLATT, a citizen of the United States of America, residing at Bridgeport, Connecticut, have **6** invented a new and useful Electric-Switch Lock, of which the following is a specification.

My invention relates particularly to inclosed switches. It has been customary to **10** provide locks and seals for preventing tampering with the box and its contents. It has also been customary to provide means for locking the handle of the switch or some interior part so as to prevent operation of **15** the switch.

My main object is to provide a simple and inexpensive construction by which it is possible to lock or fasten the box when desired and in which it is also possible to prevent **20** operation of the switch when desired by the use of the same fastening or locking means. For this purpose I provide an auxiliary device in nature of a stop, which in its preferred form is pivoted to the exterior of **25** the box and adapted to be interposed between the cover of the box and the handle of the switch. When the stop is so interposed the box cover may be fastened or locked to the body of the box so as to prevent **30** operation of the box and also prevent operation of the switch. With the stop on the exterior of the box, it acts as an indicator so that the most casual inspection will show whether or not the switch mechanism **35** is locked. There is, therefore, no danger of someone breaking or straining the mechanism in trying to operate the switch handle when it is locked as might be the case if the stop were on the interior or out of sight.

40 Figure 1 is a plan view of an inclosed switch embodying the improvements of my invention, part of the box being broken away and shown in section to show the stop mechanism and adjacent construction.

45 Fig. 2 is a side view showing the mechanism in the open circuit position with the stop in action and the cover fastened by a padlock.

Fig. 3 is a side view showing the switch **50** in the closed circuit position, the stop being disengaged.

Fig. 4 is a perspective view of one form of stop.

The particular form of interior switch **55** mechanism is immaterial to my invention.

In the form shown, there is a stationary contact 5 and a blade 6 hinged to the post 7. The conducting parts and the usual insulating base are mounted within a box having a body 8 and a cover 9 hinged thereto in some suitable manner as for instance at the point 10.

The operating handle or lever 11 is connected to the shaft 12 inside the box. The shaft is provided with a suitable arm or **65** crank 13 which may be connected to the switch blade 6 in any suitable manner as for instance by means of a link 14. A stop 15 is provided to limit the movement of the switch handle when the circuit is opened. **70**

The cover may be fastened or sealed to the body of the box when closed in any suitable manner as for instance by means of a padlock 16 whose hasp is adapted to be passed through the openings 17 and 17' in **75** the box and in the cover respectively.

In the particular form shown the stop 18 is pivoted at 19 to the outside of the box and provided with a lug or projecting part **80** 18' which extends out from the side of the box far enough to intercept the handle when the parts are in the position of Figs. 1 and 2. Preferably a part of the stop such as 18 is adapted to lie between the flange 9' of the cover and the upper edge of the body of the **85** box when the parts are in the position of Figs. 1 and 2 so that the cover performs the function not only of holding the stop down against the handle, but also of preventing the upper end of the stop from being pried out or **90** pulled away from the side of the box. A part of the cover flange may be pressed outward or embossed as at 9" to receive the corner 18 of the stop.

When the parts are in the position shown **95** in Figs. 1 and 2, the handle of the switch is obviously locked, whereas when the parts are in the position of Fig. 3, the stop is obviously disengaged and the handle free to be moved. To close the switch when the **100** parts are in the position of Fig. 2, it is necessary to remove the padlock 16 (or disengage such other sealing or fastening means as may be employed), open the cover 9 and retract the stop into the position of Fig. 3. **105** The switch handle may then be operated to close the switch.

To lock the switch handle when the parts are in the position of Fig. 3, it is simply necessary to throw the switch handle over **110**

against the stationary stop or abutment 15, open the cover 9, swing up the stop 18 to the position of Fig. 2 and again close the cover which holds the stop 18 in position with the 5 switch handle and mechanism locked open.

I claim:

1. In combination, switch mechanism including an operating handle, a box body and cover inclosing all of said mechanism except 10 the handle, means for locking the cover to box body and means independent of the locking means external to the box and adapted to be manually set when the cover is open and held in place by the cover when 15 the cover is closed for holding the operating handle.
2. In combination, a box body and a cover for said body, a switch in the box having an external operating handle and a handle-locking stop pivoted to the body, said cover overstanding a part of said stop to prevent 20 unlocking movement of said stop when the cover is closed with the stop in locking position.
3. In combination, a box body and cover, switch mechanism mounted within said box, an external operating handle therefor, a locking stop pivotally mounted on the outside of said box and adapted to be manually 25 interposed between the handle and the cover of the box when the switch is in its open circuit position, and means for holding the movable end of said stop against said box when said stop is in its locking position.
4. In combination, a box body and cover, 30

a switch mounted in the box and having an external handle, a manually movable stop pivoted to the body of the box externally and independently of the cover and adapted to be interposed between the cover and the 40 handle and means for securing the cover closed and in engagement with the movable stop.

5. In combination, a box body, a flanged cover therefor, a switch in the box having 45 an external handle, a stop adapted to be interposed between a flange of the cover and said handle and means for fastening said cover.

6. In combination, a box body, a flanged 50 cover therefor, a switch in the box having an external handle, a stop adapted to be interposed between a flange of the cover and said handle, said cover flange overlapping a part of said stop.

7. In combination, a box body and a hinged cover carried thereby, a switch in the box having an external operating handle, and a handle locking stop pivoted to the body, said cover having a portion overstanding a part of the stop to hold it when 55 in locking position.

8. In combination, a box body and a hinged cover carried thereby, a switch in the box having an external operating handle, 60 and a movable locking stop carried by the body, said cover having a flange overstanding a part of the stop to hold it when in locked position.

CLARENCE D. PLATT.
